United States Patent Office

Des. 211,366
Patented June 11, 1968

211,366

CHRISTMAS ORNAMENT OR THE LIKE

Otto Kadmon and Alice Kadmon, both of 144-37
76th Road, Flushing, N.Y. 11367

Filed Feb. 10, 1967, Ser. No. 5,757

Term of patent 7 years

(Cl. D29—1)

FIG. 1 is a front perspective view of a Christmas ornament or the like, embodying our new design,

FIG. 2 is a rear perspective view thereof, and

FIG. 3 is a rear view thereof.

We claim:

The ornamental design for a Christmas ornament or the like, substantially as shown.
